RADIO LOCATING SYSTEM FOR PRODUCING STEREOSCOPIC INDICATIONS OF OBJECTS

David E. Sunstein, Cynwyd, Pa., assignor to Philco Corporation, Philadelphia, Pa., a corporation of Pennsylvania

Application November 6, 1946, Serial No. 708,074

12 Claims. (Cl. 343—7.9)

This invention relates to radiant energy systems in which signals transmitted, retransmitted or reflected from a plurality of target objects variously disposed in space are intercepted at a receiver and utilized either directly or indirectly to provide indications of the positions of such targets relative to a selected reference point in space. More particularly it relates to methods of and means for providing a three-dimensional or stereoscopic visual presentation of the positions of said targets and their dispositions, one with reference to the other.

In embodiments of the invention hereinafter to be described, the data required, to produce a presentation of the sort just referred to, may be derived from a conventional radar or pulse-echo system utilizing, for example, an orientable antenna which both transmits pulses of high frequency energy and selectively receives reflections of said pulses from different target objects. However the invention is not limited to the use of such a system. A pulse-echo system employing separate transmitting and receiving antennae may be used in which only one antenna (which may be either the transmitter or the receiver) is directionally controllable and the other may be non-directional. Furthermore a continuous wave system, rather than one of the pulse-echo type, may be used. Still another alternative, which, for example, might be resorted to when the system is used to track friendly aircraft, consists in providing a multi-directional beacon transmitter in each aircraft and means on the ground for selectively receiving the transmissions therefrom.

In the most elementary system according to the invention, a stereoscopic presentation is produced corresponding to a virtual viewing point at the location of the directionally controllable antenna (whether this be the transmitter or the receiver or both). It may be desirable, under certain circumstances, to translate the virtual viewing point of the presentation to some arbitrarily selected point remote from the antenna. This can readily be done, as will hereinafter be set forth, by using coordinate translation means well known in the art. (See, for example, U. S. Patent 2,408,081 of September 24, 1946, to C. A. Lovell et al.)

In a conventional radar system, transmitting time-spaced pulses of high frequency energy and receiving reflections of said pulses from target objects, it is common to use the intelligence contained in the received reflected signals to reconstruct a graphic indication or plot of the targets within range of the transmitter and receiver. For this purpose a cathode ray tube or like indicator is generally used to provide a two-dimensional plot from which certain data with respect to target location can be read more or less directly. It is known to use plots of several different forms, each of which is adapted to emphasize, and to make conveniently available, certain target coordinate data. Thus, for example, the form of presentation commonly referred to as "A-Scan" provides a plot of reflected signal amplitude versus range. The so-called B and C scans yield, respectively, plots of range and elevation versus azimuth, while the "P. P. I." scan pro-

vides a polar plot of range versus azimuth angle. While each of these forms is desirable for, and peculiarly suited to, certain specific applications, none of them is suitable for use directly in a system of the sort here contemplated.

5 To obtain a true and undistorted three-dimensional or stereoscopic presentation, corresponding to direct visual observation, it is necessary, in effect, to superpose stereoscopically two presentations corresponding respectively to the images which, for example, would be produced by

10 two optical lenses having displaced parallel axes. Thus, in this instance it is necessary to reconstruct, from the data provided, for example by a radar system, indications corresponding to those which, for example, would be produced by appropriately situated cameras and which, for convenience, may be referred to as camera presentations. It is accordingly an object of the invention to provide methods of and means for obtaining such presentations utilizing the data available, for example, from a conventional radar transmitter and receiver system.

15 Given means for converting available data into visual camera presentations, it is then possible, in accordance with the invention, to supply two such means with data from separate and differently located systems to produce separate and differing presentations which, when viewed

20 stereoscopically by suitable means, will convey to the observer a three-dimensional view of objects in space corresponding, at least so far as the relative positions of the objects are concerned, to that which would be obtained by direct and unimpeded visual observation. This 25 constitutes another object of the invention.

Still another object of the invention is to provide means whereby the two displaced camera presentations needed for the production of a stereoscopic presentation can be produced from data supplied, for example, from a single 30 radar system comprising a transmitter, a receiver and an orientable antenna.

35 As hereinbefore mentioned, the data which is used to produce the camera presentations can be converted, through the application of known methods, to yield a stereoscopic presentation corresponding to a remote virtual viewing point. More specifically, in the instance of data supplied by a ground based system, the data may be converted to yield a presentation related to a virtual viewing point somewhere above the ground. When this 40 is done the difficulty may arise that it will be impossible from the presentation to determine within which of two opposed hemispheres a given target is actually situated. Hence it is another object of the invention to provide means for eliminating this ambiguity.

45 Other objects and features of the invention will become apparent from consideration of the following specification with reference to the accompanying drawings in which:

50 Fig. 1 is a diagram in tridimensional orthogonal coordinates, to which reference will be made in explaining the manner in which azimuth, elevation and range data, with respect to the positions of objects variously disposed in space, may be converted into bidimensional rectangular coordinate data for providing a bidimensional presentation corresponding to that which would be obtained by 55 visual observation from the reference point in space to which the azimuth and elevation data are referred, or from a point in space displaced in a single coordinate direction from said reference point;

55 Fig. 2 is a schematic diagram of circuits for converting azimuth and elevation data, referred to a predetermined reference point in space, into bidimensional coordinate data for providing a visible presentation of said data referred to a reference point corresponding to said predetermined reference point in space. The circuits illustrated 60 are suitable for use in the deflecting signal generator 65 of the embodiment according to Fig. 3;

65 Fig. 3 is a block diagram of a complete radar system

for providing a stereoscopic presentation indicative of the positions of objects variously disposed in space referred to a reference point corresponding to the physical location of the radar apparatus employed to provide data with respect to the azimuths and elevations of the objects;

Fig. 4 is a schematic diagram of circuits for converting azimuth, elevation and range data, referred to a predetermined reference point in space, into bidimensional coordinate data for providing a visible presentation of said data referred to a predetermined reference point in space displaced in a single coordinate direction from said first-named reference point. The circuits illustrated are suitable for use in the deflecting signal generator 95 of the embodiment according to Fig. 5;

Fig. 5 is a block diagram of a complete radar system for providing a stereoscopic presentation indicative of the positions of objects variously disposed in space referred to a predetermined reference point displaced in a single coordinate direction from the physical location of the radar apparatus employed to provide data with respect to the azimuths and elevations of the objects;

Fig. 6 is a diagram in tridimensional orthogonal coordinates, to which reference will be made in explaining the manner in which azimuth, elevation and range data, with respect to the positions of objects variously disposed in space, may be converted into bidimensional rectangular coordinate data for providing a bidimensional presentation corresponding to that which would be obtained by visual observation from a predetermined reference point in space displaced in three orthogonal coordinate directions from another reference point in space to which the azimuth and elevation data are referred;

Fig. 7 is a schematic diagram of circuits for converting azimuth, elevation and range data, referred to a predetermined reference point in space, into bidimensional coordinate data for providing a visible presentation of said data referred to a predetermined reference point in space displaced in three orthogonal coordinate directions from said first-named reference point. The circuits illustrated are suitable for use in the deflecting signal generator 173 in the embodiment according to Fig. 8; and

Fig. 8 is a block diagram of a complete radar system for providing a stereoscopic presentation indicative of the positions of objects variously disposed in space referred to a predetermined reference point in space, which reference point is displaced in three orthogonal coordinate directions from the physical location of the radar apparatus employed to provide data with respect to the azimuths and elevations of the objects.

The position of a target in space with reference to a predetermined point is conveniently specified in terms of the elevation angle (ϕ), the azimuth angle (θ) and the range (r) from the point to the target. In a conventional radar system employing a scanning antenna, the angles ϕ and θ , for a particular target, are directly related to and derivable from the orientation of the antenna structure when it is pointed at the target, as indicated by the fact that a transmitted pulse of high frequency energy is reflected from the target and intercepted by the antenna. Likewise, the range r is a function of the time required for the pulse to travel to the target and return. From the angles ϕ and θ , assuming a lens of predetermined focal length (f) located at the predetermined reference point, it is possible to specify the coordinates, in the focal plane of the lens, of the optical image of any point in space. These coordinates are independent of r inasmuch as all points in space lying on the same straight line through the center of the lens are imaged at the same point in the focal plane. If in rectangular form, the coordinates correspond respectively to the horizontal and vertical deflecting potentials which must be applied to an electrically deflected cathode ray tube to produce a camera presenta-

tion of the point in space as would be seen from the aforementioned reference point.

Referring now to Figure 1, it will be apparent that the deflecting signals E_x (horizontal) and E_y (vertical) can be expressed generally in terms of the angles ϕ and θ and the focal length f . It may be assumed that a camera presentation is to be produced of an object at point T such as would be produced by a lens of focal length f located at a reference point O, whose optical axis coincides with the axis Z-Z' of the rectangular coordinate system defined by the axis X-X', Y-Y' and Z-Z'. The elevation and azimuth angles of the point T with reference to the coordinate system are designated respectively by ϕ and θ . The point T is imaged at the point T' having X and Y coordinates E_x and E_y respectively, which correspond to the desired deflecting signals. It can readily be shown that E_x and E_y are completely specified by the following expressions:

$$E_x = f (\cot \phi \cos \theta) \quad (1)$$

$$E_y = f (\cot \phi \sin \theta) \quad (2)$$

Likewise it will be apparent that the perpendicular radial displacement r' of the point T' from the axis Z-Z' is proportional to the cotangent of the elevation angle ϕ and that the azimuth of point T' differs from that of point T by 180°.

Data with regard to the variations of ϕ and θ can readily be obtained from any conventional radar, for example, through the employment of self-synchronous motors or other similar means. These data may be utilized in a circuit of the sort shown in Figure 2 to generate the desired deflecting signals according to Expressions 1 and 2 given above. In particular it should be noted that these deflecting signals are independent of the range to point T from point O, and that hence the range data supplied by the radar, in this instance, is not used. Such range data, however, does become useful in other embodiments of the invention as will hereinafter be set forth.

In the circuit arrangement of Figure 2 the potentials impressed between the 90° point and each end of potentiometer 1 by batteries 2 and 3 correspond to the desired focal length (f) of the system. The slider on the potentiometer is moved in synchronism with the elevation angle ϕ so as to derive a potential whose value is $f \cot \phi$. This may be accomplished either by varying the displacement of the slider from the 0° center point proportionally to $\cot \phi$ or by varying its displacement proportionally to ϕ and providing, in the potentiometer, a "tapered" resistive element whose resistance varies throughout each half of its length proportionally to $\cot \phi$. Various methods of constructing such potentiometer resistance elements are well known in the art, for which reason it is deemed unnecessary to discuss their construction in detail here. It will, of course, be appreciated that such variation in displacement or resistance cannot be achieved throughout the complete range of values of ϕ , since $\cot \phi$ approaches infinity as ϕ approaches zero. This, however, does not present a serious problem, its only effect being to limit somewhat the field of view which can be reproduced in the camera presentation. The same limitation is present, usually to an even greater extent, in an optical camera. However, even this slight limitation can be overcome as will hereinafter be set forth.

The signal taken from the slider of potentiometer 1 is supplied through connection 4 to a slider 5 of a circular potentiometer 6. Potentiometer 6 is provided with a second slider 7 which may be mechanically (but not electrically) connected to slider 5 so that the two will always make contact with the resistive element at points thereon which are diametrically opposite one from the other. Sliders 5 and 7 are moved in synchronism with the azimuth angle θ , so that between points 8 and 9 there is

developed a signal $E_y = f(\cot \phi \sin \theta)$, and so that between points 10 and 11 there is developed a signal

$$E_x = f(\cot \phi \cos \theta)$$

As already pointed out, these are the required deflecting signals to yield the camera presentation. To achieve this result, as in the case of potentiometer 1, the displacement of sliders 5 and 7 may be varied non-uniformly as a function of the azimuth angle θ . Alternatively the resistance throughout each quadrant sector of the resistive element may be tapered in such a way as to produce the desired sinusoidal variation as a function of θ when the sliders are moved at a uniform rate.

In order to provide a stereoscopic presentation in the usual manner, it is necessary to provide two camera presentations corresponding to views of the object T from two different points separated by a distance which may preferably be made substantially greater than the spacing between the eyes of the observer. In this manner it is possible greatly to enhance the stereoscopic effect and thereby to increase the facility with which the observer can distinguish objects differing only slightly in range. Thus, in Figure 1, if P is a point displaced from point O by the required amount, the required data for producing the two presentations may be obtained from two separate radar equipments located respectively at points O and P. Reference is now made to Figure 3 which shows a complete system for this purpose.

The two radars 20 and 21 are equipped with antennas 22 and 23 constructed and arranged to scan both in elevation and azimuth. Although, as shown, these antennae are of the mechanically orientable type, it would be equally feasible to use, for example, antennae comprising fixed elements, whose directionalities are controllable by varying the phasing of the signals supplied to or received from the several directional elements of each. This statement applies, in fact, to the antennae in all of the systems disclosed herein. Preferably antenna 22 is caused to scan a target area in a predetermined systematic manner and antenna 23 is controlled from radar 20 through connection 24 so as to scan in exactly the same manner (i. e. so that the electrical axes of the two antennas are always parallel). Both radars 20 and 21 preferably transmit pulses of high frequency energy simultaneously, which may be achieved by controlling radar 21 from radar 20 through connection 24. Elevation and azimuth data (ϕ and θ) are supplied through connection 25 to a deflecting signal generator 26, which may be of the form shown in Figure 2 and which is adapted to provide horizontal and vertical deflecting signals E_x and E_y in accordance with Expressions 1 and 2. The horizontal deflecting signal, E_x , is supplied through connections 27, 28 and 29 to the horizontal deflecting plates (not shown) of a pair of electrically deflected cathode ray tubes 33 and 34. Likewise the vertical deflecting signal, E_y , is supplied through connections 30, 31 and 32 to the vertical deflecting plates (not shown) of the same cathode ray tubes. The electron beams of the two tubes are thereby caused to scan the screens 35 and 36 of the respective tubes according to the same pattern, as determined by the motion of scanning antennas 22 and 23.

However, it will be noted that both scanning antennas 22 and 23 will not be directed at the target object T at the same instant of time. Thus when the electrical axis of antenna 22 is directed along line 37 at point T, the electrical axis of antenna 23 will be directed along line 38 which does not intercept point T. At some later time in the scanning cycle antenna 23 will assume the broken line position 23a such that its electrical axis will be directed along line 40 so as to intercept point T while antenna 22 will assume the position, indicated by broken lines 22a, with its electrical axis directed along line 39. Thus it will be apparent that reflections of pulses successively transmitted from both antennas 22 and 23 will be reflected at different times from target T and will ar-

rive at radars 20 and 21 at correspondingly different times. Reflections received by radar 20 are transmitted through connection 41 to control the intensity of the electron beam in cathode ray tube 33. Likewise reflections received by radar 21 are transmitted through connection 42 to control the intensity of the electron beam in cathode ray tube 34. By reason of the fact that screens of tubes 35 and 36 are scanned in identical manner by their respective electron beams, the reflection from target T supplied to cathode ray tube 33 will appear at a different point on screen 35 from that at which the delayed reflection from target T supplied to tube 34 will appear on screen 36. Thus there will appear on screens 35 and 36 different camera presentations of the same target object. Similarly, different camera presentations will appear on screens 35 and 36 for other targets (not shown) within view of the scanning antennas 22 and 23. The two different camera presentations may then be presented optically, for example, through a conventional stereoscopic viewer 43 to the eyes 44 of an observer so as to provide him with a three-dimensional view of all of the objects within view of the scanning antennas 22 and 23 of radars 20 and 21.

From study of Figure 1, it will be seen that the angles ϕ' and θ' , denoting respectively the elevation and azimuth of point T with reference to point P, can be expressed in terms of the angles ϕ and θ . From this it follows that, knowing the variations in ϕ and θ , deflecting signals can be derived which may be applied to the horizontal and vertical deflecting plates of a cathode ray tube which, when its electron beam intensity is controlled by reflections received by a radar located at point O, is capable of producing a camera presentation corresponding to that which would be produced by a radar located at point P and scanning in the same fashion as the one at point O. Thus a single radar located at point O can supply all of the data required for stereoscopic presentation. The new horizontal and vertical deflecting signals E_x and E_y above referred to are given by the following expressions:

$$E_x = f \left(\cot \phi \cos \theta - \frac{OP \csc \phi}{r} \right) \quad (3)$$

$$E_y = f \left(\cot \phi \sin \theta \right) \quad (4)$$

It will be noted that the vertical deflecting signal is the same as that applied to the vertical deflecting plates of both tubes in the system of Figure 3. This is owing to the fact that point P is displaced from point O solely in the X direction. If point P were displaced in both X and Y directions, the expression for E_y would be correspondingly modified.

Referring now to Figure 4, which illustrates a circuit for generating these deflecting signals, a signal $f \cot \phi$ is derived from potentiometer 50 whose slider is moved in synchronism with the elevation angle ϕ as in the case of potentiometer 1 of Figure 2. Likewise, as in the case of Figure 2, the signal derived from potentiometer 50 is supplied through connection 51 to slider 52 of potentiometer 53 corresponding to potentiometer 6 of Figure 2. From terminals 54 and 55 of potentiometer 53 is derived a vertical deflecting signal $E_y = f(\cot \phi \sin \theta)$ according to Equation 4, and from terminals 56 and 57 of potentiometer 53 is derived a signal $f(\cot \phi \cos \theta)$ which is part of the new horizontal deflecting signal. According to Equation 3, there is to be subtracted from this latter signal a signal equal to

$$f \left(\frac{OP \csc \phi}{r} \right)$$

to yield the new horizontal deflecting signal for one of the cathode ray tubes. However, it is found more convenient in practice to add to $f(\cot \phi \sin \theta)$ a signal whose value is equal to

$$f \left(\frac{OP \csc \phi}{2r} \right)$$

to yield the horizontal deflecting signal for one tube, and to subtract from $f(\cot \phi \sin \theta)$ a signal whose value is equal to

$$f\left(\frac{OP \csc \phi}{2r}\right)$$

to yield the horizontal deflecting signal for the other tube. The deflecting signals thus produced, together with the vertical deflecting signal $E_y = f(\cot \phi \sin \theta)$, are such as to provide camera presentations corresponding to the views from points displaced respectively in opposite directions by amounts equal to

$$\frac{OP}{2}$$

from the actual location of the radar antenna.

A signal inversely proportional to r , to provide the denominator for the expression

$$f\left(\frac{OP \csc \phi}{2r}\right)$$

is derived by successively charging condenser 58, in the cathode circuit of tube 59, in response to pulses supplied to the grid of tube 59 which are timed to coincide with the transmission of pulses of high frequency energy by the radar transmitter. During the intervals between such pulses, condenser 58 discharges through resistor 60 so as to provide, across the condenser, a signal which varies substantially inversely with time following each transmitted radar pulse. The latter signal is supplied through a suitable amplifier 61 across the resistive element of a potentiometer 62. Potentiometer 62 is center-tapped to ground through resistor 63 and its slider is moved in synchronism with the elevation angle ϕ to yield a signal proportional to

$$\frac{\csc \phi}{r}$$

To this end the potentiometer slider may be moved at a non-uniform rate over the resistive element, or the resistive element may be appropriately tapered to yield the same result. The signal from potentiometer 62 is supplied to the primary winding of a transformer 64 having connected in series with its secondary winding a series resistive network comprising resistors 65, 66 and 67. Terminal 56 of potentiometer 53 is connected to a center tap on the secondary winding of transformer 64 whereby, with appropriate adjustment of resistor 66, the signals from potentiometers 53 and 62 will be combined to yield, across terminals 68, the desired horizontal deflecting signal

$$E_x = f \left(\cot \phi \cos \theta + \frac{OP \csc \phi}{2r} \right)$$

for one tube and, across terminals 69, the complementary horizontal deflecting signal

$$E_x' = f \left(\cot \phi \cos \theta - \frac{OP \csc \phi}{2r} \right)$$

for the other tube.

In the system, as illustrated in Figure 5, employing a single transmitter, receiver and antenna to provide a stereoscopic presentation, the radar 90 and its antenna 91 are located intermediate between the points O and P, the virtual viewing points for the two different camera presentations to be produced on screens 35 and 36 of cathode ray tubes 92 and 93 respectively. Azimuth and elevation information from radar 90 is supplied through connection 94 to deflecting signal generator 95 which may be of the form just described with reference to Figure 4. The vertical deflecting signal E_y is supplied through connections 96, 97 and 98 to both tubes 92 and 93, while the horizontal deflecting signals E_x and E_x' are supplied through connections 99 and 100 to tubes 92 and 93 respectively. Reflections from targets received by radar 90 are supplied through connections 101 and 102 to both

cathode ray tubes to modulate simultaneously their respective electron beams. As in the system of Figure 3, the complementary camera presentations produced on the screens 103 and 104 of the cathode ray tubes may be translated optically through a suitable stereoscopic viewer 105 to the eyes 106 of an observer to give him the desired three-dimensional impression of the space scanned by antenna 91 of radar 90.

In the immediately foregoing discussion referring to Figures 1, 4 and 5, methods and means have been disclosed for translating the virtual viewing point in one coordinate direction with reference to the actual location of the radar transmitter and receiver. In certain applications it may be desirable to translate the virtual viewing point in two or in all three coordinate directions. Thus, in the instance of a ground-based radar located at an airport and used to observe air traffic within a predetermined radius which is large compared to the average level of flight, the portion of the presentation corresponding to the average level of flight will tend to become crowded under conditions of dense traffic in the vicinity of the field. Moreover, owing to practical limitations in the construction of the $\cot \phi$ potentiometers, hereinbefore referred to, it will be impossible to present aircraft flying at low angles of elevation. This difficulty can be overcome by locating the virtual viewing points, of a stereoscopic radar system in accordance with the invention, beneath the surface of the ground. The following description and discussion relates to a stereoscopic system for providing displacement of the virtual viewing point in X, Y and Z directions in a rectangular coordinate system. Referring now to Figure 6, let it be assumed that an object at point T is to be observed from point P displaced by the amounts X_1 , Y_1 and Z_1 with reference to the point O at which a radar antenna is located. The elevation and azimuth angles ϕ_1 and θ_1 of point T with reference to point P can be expressed in terms of the elevation and azimuth angles ϕ and θ of point T with reference to point O. Likewise, as in the instance previously discussed, the expressions in terms of ϕ and θ for the horizontal and vertical deflecting signals E_x and E_y required to produce the desired camera presentation from point P can be derived and are found to be:

$$E_x = f \left[\frac{r \cos \phi \cos \theta - X_1}{r \sin \phi - Z_1} \right] \quad (5)$$

$$E_y = f \left[\frac{r \cos \phi \sin \theta - Y_1}{r \sin \phi - Z_1} \right] \quad (6)$$

In the circuit shown in Figure 7 for generating these signals, a signal which varies proportionally to r during an interval following each radar transmitted pulse is developed across condenser 110. To generate this signal, negative pulses of the form shown at 111, commencing at time t_1 corresponding to the transmission of a radar pulse and terminating at time t_2 prior to transmission of the next subsequent radar pulse, are supplied to the grid of vacuum tube 112 to render it non-conducting during the interval $t_1 - t_2$. The time constant of the RC circuit comprising resistor 114 and condenser 110 may be made such that the portion of the signal 113 developed across condenser 110 between times t_1 and t_2 is essentially linear and therefore proportional to r . This signal is supplied through an isolating amplifier 115 to a tap on circular potentiometer 116. The opposite tap of the potentiometer is grounded through connection 117. The potentiometer is provided with four rectangularly displaced sliders 118, 119, 120 and 121 which are rotated in synchronism with elevation angle ϕ . Potentiometer 116 is so constructed and operated, similarly to those of Figures 2 and 4 as hereinbefore set forth, that a signal equal to $r \sin \phi$ is developed between sliders 118 and 120, while a signal equal to $r \cos \phi$ is developed between sliders 119 and 121. The $r \sin \phi$ signal is supplied through connections 122 and 123 to the primary winding of a transformer 124.

By means of batteries 125 and 126 and potentiometer 127, whose slider is connected to one terminal of the secondary winding of transformer 124, a potential of magnitude Z_1 is subtracted from the signal in the secondary winding of transformer 124 to yield, between the other secondary winding terminal and ground, a signal equal to $r \sin \phi - Z_1$. The latter signal is supplied through connection 128, and optionally through a rectifier 129, to the divisor input terminals of dividers 130, 131, 132 and 133. The function of rectifier 129 will be set forth hereinafter.

The $r \cos \phi$ signal developed between sliders 119 and 121 of potentiometer 116 is supplied through connections 134 and 135 to the primary winding of transformer 136. Transformer 136 is provided with a pair of secondary windings, the terminals of each of which are connected to oppositely disposed taps on potentiometers 137 and 138 respectively. Each potentiometer is provided with a pair of opposed sliders which are rotated in synchronism with azimuth angle θ , and the potentiometers are so constructed and operated as to develop, between sliders 139 and 140, a signal equal to $r \cos \phi \cos \theta$, and, between sliders 141 and 142, a signal equal to $r \cos \phi \sin \theta$. By means of batteries 143 and 144 and potentiometer 145 there is subtracted, from the signal from potentiometer 137, a potential of magnitude X_1 . Also, by means of a network comprising batteries 146 and 147 and resistors 148, 149 and 150, there is added to and subtracted from the resultant signal a further small potential ΔX_1 corresponding to one-half the X displacement between the eyes of the observer. The resultant signals, appearing at opposite ends of resistor 150, are supplied through connections 159 and 160 to the dividend input terminals of dividers 132 and 133. These dividers operate to divide the dividend inputs by the divisor inputs to yield horizontal deflecting signals according to the following expressions:

$$E_x = f \left[\frac{r \cos \phi \cos \theta - X_1 + \Delta X_1}{r \sin \phi - Z_1} \right] \quad (7)$$

$$E_x' = f \left[\frac{r \cos \phi \cos \theta - X_1 - \Delta X_1}{r \sin \phi - Z_1} \right] \quad (8)$$

These are the horizontal deflecting signals needed to produce the two camera presentations for a stereoscopic presentation with a viewing point P having the coordinates X_1 , Y_1 , Z_1 .

In a similar manner, by means of batteries 151 and 152 and potentiometer 153, there is subtracted from the signal from potentiometer 138 a potential of magnitude Y_1 . Also, by means of a network comprising batteries 154 and 155 and resistors 156, 157 and 158, there is added to and subtracted from the resultant signal a further small potential ΔY_1 corresponding to one-half the Y displacement between the eyes of the observer. The resultant signals, appearing at opposite ends of resistor 158, are supplied through connections 161 and 162 to the dividend input terminals of dividers 130 and 131. These dividers operate to divide the dividend inputs by the divisor inputs to yield vertical deflecting signals according to the following expressions, which are complementary to the horizontal deflecting signals according to Equations (7) and (8):

$$E_y = f \left[\frac{r \cos \phi \sin \theta - Y_1 + \Delta Y_1}{r \sin \phi - Z_1} \right] \quad (9)$$

$$E_y' = f \left[\frac{r \cos \phi \sin \theta - Y_1 - \Delta Y_1}{r \sin \phi - Z_1} \right] \quad (10)$$

The voltage dividers 130, 131, 132 and 133 may take any one of several different forms. Each may, for example, comprise means for first reciprocating the divisor and means for then multiplying the dividend by the reciprocated divisor. Reciprocation may be accomplished by generating a frequency modulated signal whose instantaneous frequency is proportional to the divisor, in-

tegrating the modulated signal and rectifying the integrated signal to obtain a signal corresponding to the envelope of the integrated signal, which will be approximately proportional to the reciprocal of the divisor. Another method of achieving reciprocation is to employ a remote cut off tube in which, over a limited range, the plate current is approximately inversely proportional to the grid voltage.

Multiplication of the dividend by the reciprocated divisor may be accomplished, for example, by producing separate carrier signals respectively amplitude modulated by the dividend and by the divisor. These modulated carrier signals are heterodyned, one with the other, and either the sum or difference term produced by heterodyning is selected and rectified to yield a signal which is essentially proportional to the product of the two modulating signals. For optimum results under all circumstances, and particularly when the two signals to be multiplied are not appreciably different in amplitude, it is preferable, in the heterodyning process, to employ a square-law rectifier.

Alternatively the division of the dividend by the divisor signal may be achieved directly. To this end there may be employed a pentagrid tube having a remote cut off grid and a linear control grid, each being shielded from the other and from the tube plate. The dividend signal is applied to the linear grid, while the divisor signal is applied to the remote cut off grid, which is negatively biased. The tube plate current will be substantially proportional to the ratio of the grid voltages.

It will be understood, of course, that, with reference to any of the foregoing methods, a single-sided arrangement may be used if signals of but one polarity are involved, but that a push-pull arrangement should be employed where either one or both of the signals changes polarity.

In the system according to Figure 8, the scanning antenna 170 of radar 171 is assumed to be located at point O. Point P, in accordance with Figure 6, is the virtual viewing point displaced from point O in rectangular coordinates by the amounts X_1 , Y_1 and Z_1 . Camera indications corresponding respectively to the views from points P' and P'' are to be produced. Points P' and P'' are displaced in opposite directions with reference to point P by the amounts ΔX_1 and ΔY_1 . It will, of course, be understood that they might likewise be displaced in the Z direction.

Elevation and azimuth data (ϕ and θ) are supplied from radar 171 through connection 172 to deflecting signal generator 173, which may be substantially as shown in Figure 7. Horizontal deflecting signals E_x and E_x' , in accordance with Equations 7 and 8, are supplied through connections 174 and 175 respectively to cathode ray tubes 178 and 179. Likewise vertical deflecting signals E_y and E_y' in accordance with Equations 9 and 10 are supplied through connections 176 and 177 respectively to cathode ray tubes 178 and 179. Received reflected signals from radar 171 are supplied through connections 184 and 185 to cathode ray tubes 178 and 179, as in the systems previously discussed, to modulate the intensity of the electron beams in both tubes. For the reasons hereinbefore set forth, there will be produced, on screens 180 and 181 of cathode ray tubes 178 and 179, camera presentations corresponding to the views from points P' and P'' of all objects within the field of view of radar 171. These camera presentations may be viewed through stereoscopic viewer 182 by an observer whose eyes are located at 183 and who will thereby obtain the same three-dimensional impression as would be obtained by unimpeded visual observation from point P.

Referring again to Figure 7, which shows the deflecting signal generating circuits employed in the system according to Figure 8, rectifier 129 may be so poled that only divisor signals of positive polarity are supplied from connection 128 to the divisor input terminals of dividers

130, 131, 132 and 133. This is desirable when the virtual viewing point P of Figure 6 is located at a point above the surface of the ground on which the radar is located (e. g. in an aircraft). If, under such circumstances, rectifier 129 is not included in the circuit, divisor signals of positive polarity will be supplied to the divisor input terminals of the dividers for objects above the virtual viewing point, and divisor signals of negative polarity will be supplied for objects below the virtual viewing point. Obviously this would lead to confusion since it would be impossible from the stereoscopic presentation to determine which indications corresponded to objects above the virtual viewing point and which to objects below. By appropriately poling rectifier 129, divisor signals corresponding either to objects above or below the virtual viewing point may be eliminated and only those objects within a selected hemisphere whose axis parallels the Z axis may be made to appear in the stereoscopic presentation. Obviously switching means may be included to change the polarity of rectifier 129 so as to select either the hemisphere above or the hemisphere below the plane through the virtual viewing point perpendicular to the Z axis. Likewise, it would be possible to cause objects in one hemisphere to produce a stereoscopic indication in one color and to cause objects in the opposite hemisphere to appear in the same stereoscopic presentation in another color, thereby providing a convenient means of discrimination between targets in the two hemispheres.

It will, of course, be understood that the invention is susceptible of embodiment in physical forms other than those here shown and that component circuits other than those described, but adapted to produce equivalent results, may be devised by those skilled in the art based on the principles hereinbefore set forth. Numerous variations in the manner of applying these principles are likewise contemplated, which it is unnecessary to set forth here in detail. Thus, for example, the cathode ray indicators used to produce the desired camera presentations may make use of deflecting elements other than the conventional rectangularly disposed electric deflecting plates. In this event the deflecting signals applied will, in general, be of forms different from those herein prescribed. From the foregoing discussion it will be apparent, however, that, from the data supplied by the radar system, appropriate deflecting signals can be derived to meet the requirements for production of the camera presentation regardless of type of indicator employed. Accordingly the scope of the invention is to be regarded as subject only to the limitations imposed by the appended claims.

I claim:

1. In a radiant energy object position indicating system, a receiver, means including a directional antenna for causing said receiver selectively to receive energy emanating from objects variously disposed in space and having different bearings from said antenna, said directional antenna being controllable to vary its direction of maximum receptivity, said antenna direction being defined by the elevation angle which the directional axis of said antenna forms with a predetermined reference plane and the azimuth angle which the projection of said axis upon said reference plane forms with another plane normal to said reference plane, means for generating a signal substantially proportional to the product of the cotangent of said elevation angle and the sine of said azimuth angle, means for generating a signal substantially proportional to the product of the cotangent of said elevational angle and the cosine of said azimuth angle, an electron beam indicator having orthogonal deflecting elements, means for controlling the intensity of said electron beam in response to said received energy, and means for applying said signals to said deflecting elements to produce a visual presentation comprising indications of the energy received from said objects.

2. In a radiant energy object position indicating sys-

tem, a receiver, means including a directional antenna for causing said receiver selectively to receive energy emanating from objects variously disposed in space and having different bearings from said antenna, said directional antenna being controllable to vary its direction of maximum receptivity, said antenna direction being defined by the elevation angle which the directional axis of said antenna forms with a predetermined reference plane and the azimuth angle which the projection of said axis upon said reference plane forms with another plane normal to said reference plane, means for providing data with respect to the ranges of objects from which said energy is received, means for generating deflecting signals, one of said signals being a function of the cotangent of said elevation angle and the sine of said azimuth angle, the other of said signals being a function of the cotangent of said elevation angle and the cosine of said azimuth angle, and at least one of said signals being also a function of said range and of the displacement of said antenna from a predetermined point in space, an electron beam indicator having orthogonal deflecting elements, means for controlling the intensity of said electron beam in response to said received energy, and means for applying said signals to said deflecting elements to produce a visual presentation comprising indications of the energy received from said objects.

3. In an object position indicating system, a directional receiver whose direction of maximum receptivity is variable, said direction being defined jointly by the elevation angle which said direction forms with a predetermined reference plane and the azimuth angle which the projection of said direction upon said reference plane forms with another plane normal to said reference plane, an indicator comprising a bidimensional presentation device and responsive to energy received by said receiver to produce visible indications upon said presentation device, said indicator also being controllable to vary the positions of said indications upon said presentation device, means for deriving deflecting signals which are functions of said elevation and said azimuth angles of said direction of maximum receptivity, and means for controlling said indicator in response to said deflecting signals to displace said indications in one of two mutually perpendicular directions by an amount substantially proportional to the product of the cotangent of said elevation angle and the sine of said azimuth angle, and further to displace said indications in the other of said perpendicular directions substantially proportionally to the product of the cotangent of said angle of elevation and the cosine of said angle of azimuth.

4. In an object position indicating system, a directional receiver whose direction of maximum receptivity is variable, said direction being defined jointly by the elevation angle which said direction forms with a predetermined reference plane and by the azimuth angle which the projection of said direction upon said reference plane forms with a second plane normal to said reference plane, an indicator comprising a bidimensional presentation device and responsive to energy received by said receiver to produce visible indications upon said presentation device upon the reception of energy by said receiver, said indicator being controllable to vary the positions of said indications with respect to said presentation device, means for deriving deflecting signals which are functions of said elevation and azimuth angles, and means for controlling said indicator in response to said deflecting signals to displace said indications radially substantially proportionally to the cotangent of said angle of elevation and angularly substantially proportionally to said azimuth angle.

5. In a stereoscopic object position indicating system, a receiver, a pair of directional antennae whose directions of maximum receptivity are variable, said directions being defined by the elevation angles which the directional axes of said antennae form with a predetermined reference plane and by the azimuth angles which the projections of

said directional axes upon said reference plane form with a second plane normal to said reference plane, an indicator comprising a pair of bidimensional presentation devices and responsive to energy received by said receiver to produce indications on said presentation devices, said indicator being controllable to vary the positions of said indications with respect to said presentation devices, means for deriving two sets of deflecting signals, each of which is a function of the elevation and azimuth angle of one of said directional axes, means for controlling said indicator in response to said deflecting signals to displace said indications upon each of said presentation devices in one of two mutually perpendicular directions substantially proportionally to the product of the cotangent of said angle of elevation and the cosine of said azimuth angle of one of said directional axes, and in the other of said mutually perpendicular directions substantially proportionally to the product of the cotangent of said angle of elevation and the sine of said azimuth angle of said last-named directional axis, and stereoscopic viewing means for viewing said pair of presentation devices.

6. In a radiant energy object position indicating system, a receiver, means including a directional antenna for causing said receiver selectively to receive energy emanating from objects variously disposed in space, said antenna direction being defined by the angle which the directional axis of said antenna forms with a predetermined reference plane and the azimuth angle which the projection of said axis upon said reference plane forms with another plane normal to said reference plane, an indicator comprising a source of an electron beam and beam-deflecting means, means for controlling the intensity of said electron beam in response to said received energy, means for deriving signals indicative of said elevation and said azimuth angles of said antenna direction, and means for applying said signals to said beam-deflecting means to deflect said beam in one of two mutually perpendicular directions substantially proportionally to the product of the cotangent of said elevation angle and the sine of said azimuth angle, and in the other of said two mutually perpendicular directions substantially proportionally to the product of the cotangent of said elevation angle and the cosine of said azimuth angle.

7. In an object position indicating system, a directional receiver whose direction of maximum receptivity is variable, said direction being defined jointly by the elevation angle which said direction forms with a predetermined reference plane and the azimuth angle which the projection of said direction upon said reference plane forms with another plane normal to said reference plane, an indicator comprising a source of an electron beam and a bidimensional presentation device upon which said electron beam is adapted to impinge, said indicator being supplied with received signals from said receiver and being responsive thereto to produce indications of the reception of energy by said receiver, said indicator also comprising means responsive to signals supplied thereto controlledly to deflect said beam thereby to alter the positions of said indications upon said presentation device, means for deriving a signal substantially proportional to the product of the cotangent of the angle of elevation and the sine of the angle of azimuth of said direction of maximum receptivity, means for deriving a signal substantially proportional to the product of the cotangent of said angle of elevation and the cosine of said angle of azimuth, and means for supplying said last-named two signals to said beam-deflecting means to deflect said beam and to control the positions of said indications upon said presentation device.

8. In an object position indicating system, a receiver of variably directional receptivity, the direction of maximum receptivity of said receiver being defined by the elevation angle which said direction forms with a predetermined reference plane and the azimuth angle which the projection of said direction upon said reference plane

forms with another plane normal to said reference plane, an indicator comprising a source of an electron beam and a bidimensional presentation device, said indicator being responsive to energy received by said receiver from objects in space to produce visible indications on said presentation device, said indicator also comprising means for controlledly deflecting said beam to vary the positions of said indications, means for deriving deflecting signals which are functions of said azimuth and said elevation angles of said direction of maximum receptivity of said receiver, means for supplying said deflecting signals to said beam-deflecting means to deflect said beam in one of two mutually perpendicular coordinate directions substantially proportionally to the product of the cosine of said azimuth angle and the cotangent of said elevation angle of said direction of maximum receptivity and in the other of said mutually perpendicular coordinate directions substantially proportionally to the product of the sine of said azimuth angle and the cotangent of said elevation angle, means for deriving signals representative of the ranges of said objects from which said energy is received, and means responsive to said range signals for deflecting said beam additionally in at least one of said coordinate directions by an amount which is substantially in inverse proportion to the ranges of said objects to which said indications correspond.

9. In an object position indicating system, a receiver of variably directional receptivity, the direction of maximum receptivity of said receiver being defined by the elevation angle which said direction forms with a predetermined reference plane and the azimuth angle which the projection of said direction upon said reference plane forms with another plane normal to said reference plane, said receiver being controllable to vary said direction of maximum receptivity so as to effect scanning of a plurality of points in a predetermined region of space, means responsive to variations in said direction of maximum receptivity of said receiver for producing deflecting signals which are functions of the elevation and azimuth angles of said scanned points, with respect to an arbitrarily-located reference point in space, as measured with reference to said two mutually perpendicular planes, an indicator comprising a bidimensional presentation device and a source of an electron beam, and responsive to energy received by said receiver from objects located within said predetermined region of space to produce indications on said presentation device, said indicator being controllable to vary the position of said beam to effect displacement of said indications, and means responsive to said deflecting signals for controlling said indicator to displace said beam in one of two mutually perpendicular coordinate directions substantially proportionally to the product of the cotangent of said angle of elevation of said scanned points with respect to said arbitrarily-located reference point and the cosine of said azimuth angle of said scanned points with respect to said reference point, and in the other of said two mutually perpendicular coordinate directions substantially proportionally to the product of said cotangent of said last-named elevation angle and the sine of said last-named azimuth angle.

10. In an object position indicating system, a receiver comprising a directional antenna whose directional axis is orientable about a predetermined point in space, the direction of said antenna being defined by the elevation angle which said directional axis forms with a predetermined reference plane and the azimuth angle which the projection of said directional axis upon said reference plane forms with another plane normal to said reference plane, an indicator comprising a bidimensional presentation device and a source of an electron beam for producing visible indications on said presentation device upon the reception by said receiver of energy emanating from objects in space, said indicator also being controllable to deflect said beam thereby to displace said indications, means for controlling said receiver and said antenna to effect

a scanning of a plurality of points lying within a predetermined region of space, means for deriving signals indicative of the ranges of said scanned points, and means responsive to orientational motion of said directional axis, to said received energy, and to said range signals for providing indications upon said presentation device whose geometric interrelationships simulate those of a photographic image of said objects taken from an arbitrarily-located point displaced from said point of orientation of said antenna, said last-named means comprising means for controlling said indicator to displace said indications in each of two mutually perpendicular coordinate directions substantially proportionally to the fractions:

$$\frac{r \cos \phi \cos \theta - X_1}{r \sin \phi - Z_1}$$

and

$$\frac{r \cos \phi \sin \theta - Y_1}{r \sin \phi - Z_1}$$

respectively, where r is the range of an object from which energy is received, ϕ is said elevation angle, θ is said azimuth angle, and X_1 and Y_1 are the horizontal coordinate displacements and Z_1 is the vertical coordinate displacement of said arbitrarily-located point from said predetermined point of orientation of said antenna.

11. A system in accordance with claim 10, comprising, in addition, means for producing other indications of said objects upon said indicator which are displaced in one of said two mutually perpendicular directions substantially proportionally to the product of the cotangent of said angle of elevation and the cosine of said angle of azimuth, and in the other of said mutually perpendicular directions substantially proportionally to the product of the cotangent of said angle of elevation and the sine of said angle of azimuth, and stereoscopic viewing means for enabling the stereoscopic viewing of said first-named indications by one eye of an observer and of said other indications by another eye of said observer.

12. In an object position indicating system, a receiver, means including a directional antenna for causing said receiver selectively to receive energy emanating from objects variously disposed in space and lying in different directions from said antenna, said directional antenna being controllable to vary its direction of maximum receptivity, means for generating signals indicative of said antenna directions, means for producing range signals indicative of the ranges of said objects from said antenna, means responsive to said range signals for modifying said generated signals to produce modified signals indicative of the directions of said objects from a predetermined reference point displaced from said antenna location, an indicator supplied with said modified signals and with said received energy for producing a bidimensional presentation comprising indications of the directions of said objects from said predetermined reference point, and a unilaterally conductive signal transfer device included in said signal modifying means and responsive only to signals of predetermined polarity for preventing the presentation at said indicator of indications of the bearings of objects located exterior to a predetermined hemisphere, one of whose boundaries is a plane including said reference point.
